UNITED STATES PATENT OFFICE.

JOHN R. BARRETT, OF CHICAGO, ILLINOIS.

TIP FOR CORDS.

SPECIFICATION forming part of Letters Patent No. 734,500, dated July 28, 1903.

Application filed January 17, 1899. Serial No. 702,483. (No model.)

To all whom it may concern:

Be it known that I, JOHN R. BARRETT, a citizen of the United States, residing at Chicago, in the county of Cook and State of Illinois, have invented certain new and useful Improvements in Tips for Cords, of which the following is a specification, reference being had to the accompanying drawings.

My invention relates to tips for cords, and has for its object to provide an improved cord-tip having a solid or substantially solid point and a tubular portion to receive and retain the end of the cord. This object I accomplish as hereinafter described and as illustrated in the drawings.

What I regard as new will be set forth in the claims.

In the accompanying drawings, Figure 1 is a view of the blank from which the tip is formed. Fig. 2 is a view showing the blank partially wound upon the cord. Fig. 3 is an elevation of the completed tip with the cord in place. Fig. 4 is a longitudinal section of the same, and Fig. 5 is a cross-section on the line 5 5 of Fig. 4.

Referring to the drawings, A indicates the blank from which the tip is formed, said blank being of the shape illustrated in Fig. 1 and consisting of a substantially rectangular section *a* at the rear and a tapered section *b* at the front, the rear portion of said tapered section being somewhat wider than the section *a*, forming a laterally-projecting wing *c*, as shown. The rear margin of the section *a* is rounded slightly, so that when rolled up no projecting corners will be formed. The edge of the section *a* adjacent to the wing *c* is serrated, as shown at *d* in Fig. 1.

In forming the tip from the blank A the wing *c* is first rolled up solidly—*i. e.*, in spiral form—until it reaches the edge *d*. The end of the cord having been placed in position on the section *a*, the rolling of the blank is then continued, the edge *d* entering and firmly engaging the end of the cord which is

rolled up within the section *a*, as shown in Fig. 2. The result is that a pointed tip is formed having a tubular rear portion and a solid or substantially solid front portion. This construction effectually prevents the flattening of the point and highly increases the efficiency of the tip.

My invention not only includes the completed tip, but also the blank from which it is formed.

That which I claim as my invention, and desire to secure by Letters Patent, is—

1. A sheet-metal tip for cords, consisting of a spirally-rolled pointed end formed of sheet metal and a projecting attaching portion, substantially as described.

2. A sheet-metal tip for cords, consisting of a spirally-rolled pointed end and a tubular rear portion adapted to receive the cord, substantially as described.

3. A sheet-metal tip for cords, consisting of a substantially solid pointed end and a tubular rear portion adapted to receive the cord, said tip being formed from a rolled blank, substantially as described.

4. A tip for cords, having a substantially solid pointed end, and a tubular rear portion adapted to receive the cord, said tubular portion having a serrated edge which engages the cord, substantially as described.

5. A tip-blank, consisting of a substantially rectangular rear section *a* and a tapered front section *b*, the latter section having a wing *c*, the whole being of thin metal capable of being rolled up to form a tip, substantially as described.

6. A sheet-metal tip-blank, consisting of a substantially rectangular rear section *a* having a rounded rear end and a tapered front section *b*, the latter section having a wing *c*, substantially as described.

JOHN R. BARRETT.
